UNITED STATES PATENT OFFICE.

MARION F. WOOTEN, OF CHARLOTTE, NORTH CAROLINA, ASSIGNOR, BY MESNE ASSIGNMENTS, TO AMERICAN AUTOMATIC SODA FOUNTAIN COMPANY, OF CHARLOTTE, NORTH CAROLINA, A CORPORATION OF NORTH CAROLINA.

SODA-WATER-DISPENSING APPARATUS.

1,288,357.

Specification of Letters Patent. Patented Dec. 17, 1918.

Application filed June 28, 1915. Serial No. 36,757.

To all whom it may concern:

Be it known that I, MARION F. WOOTEN, a citizen of the United States of America, and a resident of Charlotte, county of Mecklenburg, and State of North Carolina, have invented certain new and useful Improvements in Soda - Water - Dispensing Apparatus, of which the following is a full and clear specification, reference being had to the accompanying drawing, in which—

Figure 1 is a vertical sectional view of an apparatus embodying my invention; and

Fig. 2 is a detail view hereinafter described.

The object of this invention is to provide simple mechanism for dispensing simultaneously a measured quantity of syrup and a measured quantity of water under pressure, whereby the apparatus will deliver to the customer a drink of soda water properly mixed with the desired syrup, as more fully hereinafter set forth.

In the drawings, *a* designates a syrup tank and *b* a trap chamber connected thereto so as to fill by gravity through a passage containing a valve *c*. This chamber *b* is connected by a conduit *d* with the interior of a discharge nozzle *e*, this nozzle being arranged to discharge downwardly as usual.

In the conduit *d* is a valve *f*.

Connected to the nozzle *e* is a trap chamber *g* connected by pipe *h* to the cooling coil *i* of a suitable carbonated-water tank. Ingress of water under pressure to chamber *g* is controlled by valve *j*, and its egress through nozzle *e* is controlled by valve *k*. A vertically moving rod *l* is attached by a pin and slot connection to four arms *m*, which are respectively connected to the valves *c*, *f*, *j* and *k*, whereby these valves are simultaneously operated by the vertical movement of the rod *l*. The valves are so adjusted that when the rod is moved downwardly the valves *f* and *k* will open and the valves *j* and *c* will close.

The rod *l* is raised and lowered by means of a horizontal shaft *n* journaled in a casing and provided with a gear wheel *o*, which wheel *o* through the medium of an intermediate idle gear *p* engages a toothed rack on the rod *l*, so that by turning said shaft *n* (preferably by means of a crank *q*) to the right, the rod *l* will be pushed downwardly, and by turning the shaft in the opposite di-

rection will be raised. Any suitable coin-controlled devices may be used in connection with my apparatus.

In the coin-controlled devices shown, a downwardly inclined coin-receiving tube *r* is provided. The coin passage to this tube is restricted by shoulder *s*, which is arranged coincident to the lateral passage *t*. A coin of the proper thickness will strike shoulder *s* and be deflected into passage *t* and thence be discharged into a coin cup *u*, but should the coin be thinner than the predetermined coin, it will not strike shoulder *s* but will remain in the main passage and be discharged at the end of the tube *r*, at a point away from the cup *u*.

The cup *u* is attached to lever *v* pivotally mounted adjacent to a wheel *w* attached to shaft *n*, said lever being provided with an arm *x* which bears gravitatingly upon the periphery of wheel *w* and normally tends to drop into a notch *y* formed in the periphery of the wheel. Attached to the shaft *n* is a convolute spring *z* adapted to be tensioned when the shaft *n* is rotated to the right.

When the upper valves *c* and *j* are open, the shaft *n* is locked by the arm *x* and the spring *z* is without tension. With the parts in this position, the two trap chambers will be filled from their respective sources of supply. Upon the dropping of a coin into cup *u*, the weight of the coin will be sufficient to overbalance the normal and preponderating weight of the arm *x* and thus cause the cup end of the lever to descend. This descent is sufficient to release the wheel *w*, but is not sufficient to discharge the coin, this restricted descent being dependent upon the throwing upon the shaft *n* the finger *a'* directly under the cup. When the parts are thus released, the operator turns shaft *n* to the right, thus winding up spring *z*, closing valves *c* and *j* and opening valves *f* and *k*.

The carbonated-water under pressure in chamber *g* will be forcibly discharged, and this forcible discharge will, by suction, assist the action of gravity in emptying the syrup chamber *b* of its charge, the water and the syrup being at the same time thoroughly mixed. Upon the complete discharge of the liquids, the operator will release the crank handle *q* and the spring *z* will restore the parts to normal, the rotation of the shaft *n* having previously permitted the

coin cup to descend far enough to give the bottom of the coin cup a sufficient downward inclination to discharge the coin by gravity, thereby permitting the arm *a* to gravitate 5 against the periphery of lock wheel *w* and be in position to lock the devices as soon as the wheel *w* is rotated far enough to bring its notch *y* in line with the arm *a*. The spring will be strong enough to raise the rod *l* and 10 thus close the bottom valves *f* and *h* and open the top valves *c* and *j*, thereby permitting the trap chambers to refill. An air pipe *b'* is attached to the syrup chamber *b*, this air pipe having its upper end open and extended to a point above the level of the 15 liquid in the tank *a*, the purpose of this pipe being to permit quick discharge of syrup from tank chamber *b* as well as quick refilling thereof.

20 It will be understood, of course, that each apparatus will consist of a number of separate sets of the devices I have described, so as to thereby give the customer his choice in the matter of selecting syrups. It will 25 be understood also that the details of my apparatus may be departed from without departing from the spirit of my invention.

It will be observed that a feature of importance lies in having the syrup discharge 30 pipe *d* enter the nozzle *e* of the carbonated water vessel, whereby the discharge of the water under pressure will exert a suction action on the discharging syrup and thus

insure the complete emptying of the syrup vessel *b* during the discharge of the carbonated-water and also insuring a thorough mixture of the syrup and carbonated-water. 35

Having thus described my invention, what I claim is—

In a dispensing apparatus of the class set 40 forth, the combination of a carbonated-water trap chamber and a source of pressure supply therefor, a syrup chamber and a gravity source of supply therefor, a nozzle means into which said two trap chambers 45 discharge, separate valves for the inlets and outlets of said chambers, means for simultaneously opening the upper valves and closing the lower valves and vice versa, said means embodying a rotating shaft located 50 above said trap chambers and carrying a gear, a vertical rack-bar engaging said gear and depending on a line between the trap chambers, arms connecting this bar to all of said valves, and a spring connected to 55 said shaft and adapted to be tensioned when said shaft is rotated to move said rack-bar downwardly to open the discharge valves of said chambers, whereupon when said shaft is released the spring will return the 60 parts to normal and thus keep the inlet valves open and the outlet valves closed.

In testimony whereof I hereunto affix my signature.

MARION F. WOOTEN.
